UNITED STATES PATENT OFFICE.

VALENTINE SCHUCK, OF NEW YORK, N. Y., ASSIGNOR TO THE SUTRO BROS.
BRAID COMPANY, OF SAME PLACE.

DESIGN FOR BRAID.

SPECIFICATION forming part of Design No. 23,960, dated January 29, 1895.

Application filed December 15, 1894. Serial No. 581,977. Term of patent 14 years.

To all whom it may concern:

Be it known that I, VALENTINE SCHUCK, of the city, county, and State of New York, have invented and produced a new and original 5 Design for a Braid, to be used in trimming garments and otherwise by way of ornamentation, of which the following is a specification, reference being had to the accompanying drawing, showing the arrangement of the 10 different parts, the colors of which may be varied without changing the character of the design.

In the drawing *b, b*, are cords or strands curving around opposite edges of flat braid *a* at regular intervals, and *c, c*, are cords or strands which appear simultaneously on opposite edges at predetermined points of contact of *b, b*, with the outer edges of the braid, and then gradually approaching each other 20 meet and disappear in a point at the center of the braid.

To the casual observer the cords or strands

b and *c* are seemingly one and the same on either side of the braid, apparently starting at a point between the center and the edge of 25 the braid; first curving outwardly until the edge of the braid is reached and then curving inwardly toward the center. This characteristic, appearing simultaneously on opposite sides, produces the heart-shape figure, as 30 seen in the drawing.

The cords or strands, *b* and *c*, are slightly raised above the surface of the braid, so that the heart-shape figure is represented in outline, the interior consisting of the braid face. 35 The heart-shape figure is reproduced with regularity throughout the length of the braid.

I claim—

The design for a braid as herein shown and described.

VALENTINE SCHUCK.
